PC(57) **CLAIM**

The ornamental design for a jewelry stand, as shown and described.

DESCRIPTION

FIG. 1 is a front view showing my new design for a jewelry stand;

FIG. 2 is a back view thereof, the opposite side being a mirror image;

FIG. 3 is a bottom view thereof;

FIG. 4 is a top view thereof;

FIG. 5 is a side view thereof;

FIG. 6 is another side view thereof;

FIG. 7 is a perspective view shown from the front side thereof; and,

FIG. 8 is another perspective view shown from the back side thereof.

1 Claim, 8 Drawing Sheets(56)
